UNITED STATES PATENT OFFICE.

ARTHUR E. BLOFIELD AND JACOB J. LINK, OF NEW YORK, N. Y.

CLASP.

1,111,354.

Specification of Letters Patent. Patented Sept. 22, 1914.

Original application filed April 24, 1912, Serial No. 692,861. Divided and this application filed May 12, 1913. Serial No. 767,031.

To all whom it may concern:

Be it known that we, ARTHUR E. BLOFIELD and JACOB J. LINK, a citizen of the United States and a subject of the Emperor of Russia, respectively, and residents of the borough of Manhattan, city, county, and State of New York, have invented certain new and useful Improvements in Clasps, of which the following is a description.

Our invention relates to clasps, and is a division of our Patent No. 1,061,259, granted May 13, 1913, entitled "Bed coverings". The said application relates chiefly to bed coverings, particularly those designed to cover infants in their cribs. It also however described an improved clasp, which we described as preferably used for securing the edges of the blanket or top covering in the said improvements in bed coverings, but 20 which as stated, may also advantageously be used in other connections.

This clasp comprises the subject matter of the present application, and our object is to provide an improved device of this character, adapted for securing coverings, garments or the like, which will give an absolutely secure grip, will be tightened in accordance with the pull of the garment or material secured thereby, upon the same, 25 will not tear the fabric to which it is clasped, and will readily secure materials of different thicknesses.

Other objects of our invention comprise the provisions of parts and combinations of elements more fully described hereinafter, and particularly pointed out in the appended claims.

Attention is hereby directed to the accompanying drawings, forming part of this 40 specification, in which

Figure 1 represents a longitudinal section of one form of our improved clasp; Fig. 2 is a cross section taken on line 2-2 of Fig. 1, and Fig. 3 is a top plan view of the clasp 45 shown in Fig. 1.

Referring to the drawings, the clasp is provided with a metallic loop 1, which is secured to the smaller end of a wedge shaped member 2 preferably formed of pressed metal. A strap or other connection, 3, through which a pull will be transmitted to the clasp when the latter is in gripping engagement with the object to be secured, may be attached to the loop 1. The clamping 50 jaws 4 and 5 in the preferred form of clasp

are pivotally mounted upon the pin 6 surrounding which is a spring such as the spiral spring 7, illustrated, and the two ends of which press the jaws 4 and 5 into open position. The lower jaw preferably carries a pad 8 of rubber or other similar material between which and the end of the jaw 4 the material to be clasped is pressed. The jaws 4 and 5 are mounted, as shown in the drawings, to slide upon one face of the wedge shaped member 2, the tail end of jaw 4 preferably being provided with a portion 9 bent substantially at right angles to the jaw and bearing upon the surface of the wedge, this extension 9, if desired, having lugs 10 bearing on the two sides of the wedge member. The upper jaw 4 has an extension or stirrup 11 extending downwardly from its two sides and extending around the bottom of wedge member 2, where its two ends may be secured together, to form a complete loop between which and the lower surface of the lower jaw 4 the wedge member 2 is adapted to reciprocate. The length of the sides of the stirrup is so chosen in relation to the thickness of the wedge member 2 that the jaws of the clasp are in open position, when the stirrup 11 is at the smaller end of the wedge, and the jaws are gradually closed by the movement of the wedge through the stirrup so that when the stirrup has reached such a position that the clamping ends of the jaws are directly over the large end of the wedge member 2, the jaws will be entirely closed.

It should be noted that wedge member 2 constitutes the operative member of the clasp, the strap 3 or other supporting connection through which a pull may be imparted to the clasp, being connected to the small end of the wedge so that the greater the pull upon the small end of the wedge, the more firmly will the jaws grip the material held thereby. That is to say, when the clasp is in operation, a constant pull may be transmitted to the device through the supporting connection 3 which may be of elastic webbing or the like, which will cause the jaws to grip the material held thereby more tightly, and similarly the pull of the material held by the jaws, or the weight thereof, will cause the jaws to grip the same more tightly, the greater the pull, since the upper end of the wedge is held or supported as stated. It also should be un-

derstood that when the jaws are in closed position they are directly over the large end of the wedge which is so formed as to furnish a rigid support for the same. The 5 wedge member 2 is preferably formed of metal bent into U shape in cross section as shown in Fig. 2.

It should be understood that while we have particularly described for purpose of 10 illustration the preferred form of our invention, the invention is not limited thereto but is as broad as is indicated by the following claims:—

Having described our invention what we 15 claim as new and desire to protect by Letters Patent is:—

1. A clasp comprising a wedge-shaped operating member having means for connecting a supporting strap thereto at the smaller 20 end thereof, a pair of gripping jaws hinged together mounted to slide upon one exterior face of said member with the operative ends of said jaws directed toward the larger end of said member, the upper of said jaws having a stirrup extending around the lower jaw and said member, for slidably coating with the latter to position said jaws and close the same when they move toward the larger 25 end of said wedge member, the said member and jaws being so arranged and proportioned that the operative ends of said jaws,

when in closed position, are directly above the large end of said wedge member, substantially as described.

2. A class comprising a pair of gripping-jaws hinged together at one end, one of said jaws being provided with a stirrup directed transversely to the face of said jaw, and a wedge-shaped operating member slidably mounted within said stirrup to reciprocate 40 between the same and the exterior surface of one of said jaws, longitudinally of said jaws, the said parts being so arranged that the large end of said member forms a rigid support for the operative ends of said jaws 45 when the latter are in closed position, and said member being provided at its smaller end with means for connecting a supporting strap thereto so that a pull transmitted therethrough will draw said member 50 through said stirrup to close said jaws, and the weight or pull of the material gripped by said jaws will increase the grip of said jaws, substantially as described.

This specification signed and witnessed 55 this 7th day of May, 1913.

ARTHUR E. BLOFIELD,
JACOB J. LINK.
